His attys.

UNITED STATES PATENT OFFICE.

ALBERT VETTER, OF TOLEDO, OHIO.

AUTOMOBILE-TOP.

1,299,637.

Specification of Letters Patent.

Patented Apr. 8, 1919.

Application filed April 25, 1918. Serial No. 230,685.

To all whom it may concern:

Be it known that I, ALBERT VETTER, a citizen of the United States, and resident of Toledo, in the county of Lucas and State of Ohio, have invented a certain new and useful Automobile-Top; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

This invention relates to automobile tops, and has for its primary object the provision of improved means for securing the covers to the top frames of automobiles in an easy and quick manner without the use of securing tacks or the like, whereby to facilitate the upholstery work on tops of this character and to lessen the expense incident thereto. Further objects and advantages of the invention will be apparent from the following detailed description thereof.

While the invention, in its broader aspect, is capable of embodiment in numerous forms, a preferred embodiment thereof is illustrated in the accompanying drawings, in which—

Figure 1 is a side elevation of the upper portion of an automobile body with the top thereof raised and in longitudinal section. Fig. 2 is an enlarged fragmentary view of the top, as shown in Fig. 1, with parts broken away and removed. Fig. 3 is an enlarged bottom plan view of one of the longitudinally extending pad strips of the top, with parts broken away. Fig. 4 is an enlarged fragmentary bottom plan view of the top, with parts broken away and removed. Fig. 5 is an enlarged cross-section of a side portion of the top, and Fig. 6 is a detail of a portion of one of the rear tension straps of the top and its anchors.

Referring to the drawings, 1 designates the body of an automobile and 2 the top frame thereof, in the present instance, of the one-man type, which frame is provided with the customary rear, intermediate and front cover supporting bows 3, 4 and 5.

The top covering 6 extends from the front bow 5 over the intermediate and rear bows and thence down at the rear and is secured at its lower rear edge to the body back by pivot-studs 7, or in any other suitable or

convenient manner. The cover 6 has its front edge extending down at the front side of the front bow 5 and provided with a plurality of transversely spaced tabs 8, which are drawn tightly around the bottom and rear sides of the bow 5 and removably engaged to the rear side of the bow by pivot-studs 9, or in any other suitable manner. The cover 6 is also provided at its upper rear corner at its point of engagement with the rear bow 3 with a plurality of transversely spaced tabs 10, which extend around the bow and are removably engaged at their free ends to the front side of the bow by means of pivot-studs 11, or in any other suitable manner. In most top covers a seam 12 (Fig. 4) is provided at the upper rear corner thereof and if such seam is present the tabs 10 are preferably joined at their inner ends therewith. It is thus evident that the cover is firmly held stretched over the top bows by the engagement of the tabs 8 and 10 at the front and rear edges thereof around the respective bows 5 and 3, and that such stretching is also assisted by the securing of the lower edge of the cover-back to the body 1.

It is customary in most tops to provide a padding strip 13 extending from the front to the rear edge thereof along each side portion to fill out or assist the bows in shaping the cover at the curved sides thereof, such strips being tacked to the bows over which it extends together with the cover. In the present instance, the padding strips 13 are made easily removable from the bows by providing a plurality of hooks 14, preferably of metal, at each end thereof for engaging around the front and bottom edge portions of the respective front and rear bows of the top frame. The hooks 14 may be secured in any suitable manner to the front edge portion of the padding strips, but for the purpose of strength are preferably attached to cross metal strips 15, which are embedded in the end portions of the padding strips. The spacing of the hooks 14 is sufficient to permit the fitting of the adjacent cover-tabs 8 and 10 therebetween, as best shown in Fig. 4. The padding strips 13 are provided preferably at their inner edge portions, over each intermediate bow 4, with an upward U-shaped clip 16, which is adapted to be sprung down over the respective bow. In order to yieldingly retain these clips in position on the bows, each is

preferably provided with an indent 17, which fits into a recess provided in the bow. It is also preferable to provide one of the hooks 14 at each end of a strip with an indent 18 (Fig. 3) for engaging within a registering recess in the coacting side of the engaged bow to prevent a shifting of the padding strips transversely of the top.

- 5 Each padding strip 13 is preferably provided along the inner edge thereof with a longitudinally extending strap or tape 19, which extends from one end to the other of the strip and thence from the rear end thereof down to the back portion of the body 1 to which it is firmly anchored, preferably in an adjustable manner, as illustrated in Fig. 6. The front end of the tape 19 is anchored to one of the hooks 14 at such end or to the cross-strip 15 and to the rear end of the 20 padding strip so that a longitudinal stress is exerted thereby to the padding strip throughout its length.

15 It is evident with my improved top covering that such covering and the padding members therefor may be easily and quickly secured to a top frame or removed therefrom, thereby materially lessening the work and expense incident to the securing of covers on the top frames of automobiles 30 or the like.

25 I wish it understood that my invention is not limited to any specific construction, arrangement or form of the parts, as it is capable of numerous modifications and 35 changes without departing from the spirit of the claims.

Having thus described my invention, what I claim as new, and desire to secure by Letters Patent, is—

- 40 1. In an automobile top, the combina-

tion with the frame, cross-bows and the top cover, of padding strips for the cover extending over the cross-bows, hooks at the ends of said strips for releasably engaging the respective front and rear cross-bows, and means on the strips for releasably engaging the intermediate cross-bows.

45

2. In an automobile top, the combination with the frame, cross-bows and the top cover, of padding strips for the cover extending over the cross-bows, means at the ends of said strips for releasably engaging the front and rear cross-bows, and a tension strap extending from one end to the other of each of said strips and from the rear end 50 thereof to form an anchoring member.

55

3. In an automobile top, the combination with the frame, cross-bows and the top cover, of padding strips for the cover extending over the cross-bows, hooks at the ends of said strips for releasably engaging the respective front and rear cross-bows, means on the strips for releasably engaging the intermediate cross-bows, and means extending from the rear ends of the strips and 60 forming anchors therefor.

65

4. In an automobile top, the combination with the frame, cross-bows and the top cover, of padding strips for the cover extending over the cross-bows, hooks at the 70 ends of said strips for releasably engaging the respective front and rear cross-bows, means on the strips for releasably engaging the intermediate cross-bows, and a tension strap extending from one end to the other 75 of each of said strips and from the rear end thereof to form an anchoring member.

75

In testimony whereof I have hereunto signed my name to this specification.

ALBERT VETTER.
